UNITED STATES PATENT OFFICE.

EDWARD F. AYRES AND TIMOTHY H. FOSTER, OF DANBURY, CONNECTICUT.

DESIGN FOR A HEEL-PLATE FOR RUBBER HEELS.

SPECIFICATION forming part of Design No. 31,701, dated October 17, 1899.

Application filed September 9, 1899. Serial No. 730,025. Term of patent 14 years.

To all whom it may concern:

Be it known that we, EDWARD F. AYRES and TIMOTHY H. FOSTER, citizens of the United States, residing at Danbury, in the county of 5 Fairfield and State of Connecticut, have invented and produced a new and original Design for Heel-Plates for Rubber Heels; and we do hereby declare the following to be a full, clear, and exact description of the invention, 10 such as will enable others skilled in the art to which it appertains to make and use the same.

Referring to the accompanying drawings, Figure 1 is a plan view showing a heel-plate embodying our design, and Fig. 2 is a sectional elevation at the line $x x$ of Fig. 1.

Similar numbers of reference denote like parts in both figures of the drawings.

Our newly-invented design is applied to a heel-plate which has solid and raised wearing-surfaces at its rear end and raised wearing-pins projecting from the plate portion, while there is an opening in the central portion of the heel-plate, which opening is spanned on one 20 side of the heel-plate by a Y-shaped bridge, while dovetailed notches are formed in the 25 rear edge of said raised wearing-surface.

The essential feature of our design consists of a general horizontally-disposed plate hav-

ing a central opening bridged by a Y-shaped bridge, said plate having wearing-pins projecting therefrom and a wearing-surface projecting from the rear end thereof, said surface having dovetailed notches in its rear edge and radially-disposed grooves within its face, which grooves converge toward a common center.

1 is the plate proper; 2, the raised wearing-surface at the rear thereof; 3, the wearing-pins projecting from the plate; 4, the opening in said plate; 5, the Y-shaped bridge 30 spanning said opening on one side of the plate; 6, the dovetailed notches in the rear edge of said wearing-surface, and 7 are the radially-disposed grooves within the face of said surface.

We claim—

The design for a heel-plate for rubber heels, substantially as shown and described.

In testimony whereof we affix our signatures in presence of two witnesses.

EDWARD F. AYRES.
TIMOTHY H. FOSTER.
